CLAIM

The ornamental design for a modular display rack, as shown and described.

DESCRIPTION

FIG. 1 is a perspective view of a modular display rack showing my new design;

FIG. 2 is a left side elevational view thereof;

FIG. 3 is a top plan view thereof; and

FIG. 4 is a rear elevational view thereof;

FIG. 5 is a perspective view of a modified embodiment of the modular display rack shown in FIG. 1;

FIG. 6 is a left side elevational view thereof;

FIG. 7 is a top plan view thereof; and

FIG. 8 is a rear elevational view thereof.
